UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

CALL-DISTRIBUTING SYSTEM.

1,393,727.

Specification of Letters Patent.

Patented Oct. 11, 1921.

Application filed November 28, 1919. Serial No. 341,167.

To all whom it may concern:

Be it known that I, SAMUEL B. WILLIAMS, Jr., a citizen of the United States, residing at Brooklyn, in the county of Kings, State of New York, have invented certain new and useful Improvements in Call-Distributing Systems, of which the following is a full, clear, concise, and exact description.

This invention relates to telephone exchange systems, and more particularly to systems of the type employing automatic switches for distributing calls to the connecting circuits of operators' positions.

The object of the invention is to provide equipment at a manual exchange by means of which a calling line may be extended with a minimum of delay to an operator's position, and by means of which a plurality of calls may be simultaneously initiated in the same group of subscribers' lines without interference.

Heretofore in call distributing systems employing power driven switches of the panel type, such for example as disclosed in the patent to S. B. Williams, Jr., Serial No. 1,304,641, issued May 27, 1919, the lines terminating in the exchange have been divided into groups of 500 lines each, each group being served by a plurality of line finders.

Each line finder is equipped with ten brush sets arranged to hunt over the ten banks to which the lines of the group are connected. Thus, each group of lines is subdivided into groups of 50 lines each, each subgroup having individual thereto a so-called group circuit. Common to ten of these group circuits is a starting circuit which is arranged to cause one of the finders which has been pre-selected by the advanced starter wire circuit

to start, the particular brush set which is tripped being dependent upon the group circuit serving the group in which the calling line is situated. The group circuit is so coordinated that only one finder may be started upon the initiation of a single call, other calls in the same group of 500 lines being delayed for a predetermined interval of approximately two seconds. In order to provide for continuous service, an elaborate arrangement of alarm lamps, signals, keys and relays has been necessary.

This invention is especially directed toward the provision of improved circuits by

means of which the calling lines of a group are first connected through quick-acting switches of small capacity to an operator selecting circuit, and subsequently connected directly to an idle cord of the selected operator's position by relatively slow operating switches of large capacity. The nature of the calling line and the class of service to which the line is entitled is made evident to the operator by means of a class of service indicator assigned to the operator's position, immediately upon the extension of the calling line to the position, and the further extension of the line is made by means of the selected cord circuit in accordance with such indication and in accordance with instructions received from the calling subscriber. Upon the establishment of a connection to an idle cord circuit by the slow operating switches the quick-acting switches employed in the preliminary connection revert to common use.

It is the purpose of this invention to eliminate the use of group circuits and the attendant equipment by providing quick-acting line finders in the place of each group circuit, thus effecting a saving in the cost of equipment and a considerable saving of time for completing the connection. By the provision of means for effecting a quick connection with an operator's position, it is not necessary to provide main line finders which operate quickly, and consequently finders having a smaller number of brush sets for coöperation with large subgroups of lines may be employed with a further saving in cost of equipment.

One feature of this invention is the provision of quick-acting line finders each having access to a relatively small group of the lines of the main group, and slow-acting line finders each having access to lines of the entire group.

Another feature of this invention is the provision of means for extending the calling line temporarily to an idle operator's position and for warning the operator of a call incoming over some cord of the position.

Another feature resides in the provision of an allotting mechanism to govern the precedence of extension of calling lines to cords of the operator's position.

A still further feature resides in the pro-

vision of mechanism at the operator's position for indicating the nature of the calling line and the class of service to which it is entitled.

- 5 Other features relate to the general organization of equipment at a manual exchange, the grouping of the various units, and the detailed construction of the various parts involved in these units, which will be 10 set forth in the following description of the preferred embodiment of the invention.

It will be obvious to those skilled in the art that this invention is not limited to the particular type of equipment disclosed, but 15 is applicable to systems employing other well-known switching and indicating devices.

The invention is illustrated in the accompanying diagrammatic drawings in which;

- 20 Figure 1 shows one line of a main group of subscribers' lines, a line finder switch for making a connection therewith, an operator's cord circuit selector switch for extending a connection from the line to a cord circuit 25 and linked to the line finder switch, together with the associated circuits and apparatus through the medium of which the switches are controlled.

Fig. 2 shows a portion of an operator's 30 cord circuit, and the necessary apparatus for charging calls, ringing-back on party line calls, and listening-in and out on established connections;

Fig. 3 shows the calling end of the operator's cord circuit, together with class of 35 service signal lamps, and the circuit and apparatus through the medium of which the functions of the cord circuit are sequentially controlled.

- 40 Fig. 4 shows a primary line finder switch for making a preliminary connection with subscriber's lines of a subgroup together with the associated circuits for controlling it, the wipers and starting relay of a similar 45 finder being indicated by the dotted enclosure;

Fig. 5 shows a secondary line finder switch for making connection with lines extended through the circuits of primary line finders, 50 an operator's position finding switch for further extending a call to an idle operator's position, a finder selector for selecting paired line finder and cord selector switches, together with the associated circuits and apparatus through the medium of which the 55 switches are controlled; and

Fig. 6 shows the circuits common to an operator's position for selectively controlling the class of service signal lamps.

- 60 The figures taken together with Fig. 2 at the right of Fig. 1, Fig. 3 at the right of Fig. 2 and Figs. 4, 5, and 6 placed beneath Figs. 1, 2, and 3, respectively, illustrate as much of a complete organization as is necessary 65 to impart an understanding of the

construction and mode of operation of the system.

General Description of Apparatus.

A single telephone line of a main group 70 of 500 lines is shown in Fig. 1, it being understood that there are as many groups as are necessary to accommodate the lines terminating in the exchange. The main groups of lines are preferably divided into ten minor 75 subgroups of 50 lines each, each subgroup being served by groups of primary line finders having a capacity of 50 lines each, and are also divided into five major subgroups of 100 lines each, each subgroup of 100 lines 80 being served by one of the brush sets of each main line finder having access thereto. It would, of course, be possible to slightly increase the rapidity of line selection by reducing the capacity of the primary line 85 finders to 30 lines each, whereby the main groups of lines would be reduced to 450 lines each divided into 15 minor subgroups accessible to 15 groups of primary finders and divided into five major subgroups of 90 90 lines each served by five brush sets on the main line finders, but this reduces the capacity of the main line finders to 450 lines necessitating both a greater number of primary and main line finders. The line has 95 associated with it at the central office a line relay 8, a cut-off relay 9 and, if it is a message register line, a message register (not shown). Each line is also provided with one or more spring jacks 10 by means of 100 which connection may be made with the line when a connection is extended thereto. The line represented as a calling line in Fig. 1 and the line shown as a called line in Fig. 3

may be lines of the same character similarly 105 equipped and located at the same exchange; or the lines may be located at different offices. In the present instance the line shown in Fig. 3 is not illustrated with line 110 finder bank terminals or with equipment for controlling line finders. The line A, shown in Fig. 1, is illustrated as provided with multiple terminals in the banks of main line finders LF and of primary line finders PLF, and with a starting circuit 115 leading to primary line finder starting relays of all primary line finders having access to the subgroup of lines in which the line A is located, the starting relays being common to the subgroup of lines.

The groups of lines have access to different operators' positions and the circuits and apparatus common to each such position through the medium of primary line finders PLF, secondary line finders SLF and operator's position finders OPF, shown in Figs. 4 and 5. In the particular system illustrated, it is assumed that there are 30 operators' cords each accessible for extending a call. The operators' cords being grouped 120

into two positions of 15 cords each, although, if desired, the operators' cords could be divided into 1, 2, 3 or more groups. The switches PLF, SLF, and OPF are all of the 5 well-known step-by-step type in which a stepping pawl operates a ratchet wheel to which are connected brushes or wipers adapted to travel over the contacts of an arcuate terminal bank. These brushes or 10 wipers are so arranged that for each step of the operating magnet the brushes or wipers engage a corresponding set of terminals. The primary finder switches and the operator's position finders are each provided with six wipers and the secondary 15 finder switches are each provided with five wipers. These switches have no normal position but stop in whatever position they are placed by their respective operating magnets. 20

The main line finders LF and cord selectors CS are not novel in themselves and have therefore been shown merely diagrammatically. These switches are substantially like 25 the switch illustrated and described in the patent to J. L. McQuarrie, No. 1,177,044, issued March 28, 1916. The line finder and cord selector are alike in all essential respects. Each comprises a longitudinally 30 movable shaft 1 carrying as many sets of brushes 2 as there are groups of stationary terminals to be engaged. To move the shaft up, a depending extension of the shaft is brought into engagement with the constantly 35 rotating power roller 3 by means of an idler wheel operated by the updrive magnet; and to move the shaft down the extension is brought into engagement with the power roller 4 by means of an idler wheel operated 40 by the downdrive magnet.

Normally the brushes of each of the sets 2 are held apart so as to clear the associated terminals by means of a separating cam (not shown) located between the innermost 45 brushes of the set. The brushes are tripped or released by means of trip magnets, such as 115. Each of these trip magnets when energized rotates an associated trip rod 5 that extends transversely to the switch 50 shafts 1, and carries as many trip fingers 6 as there are finder switches in the group. The trip rod in rotating brings all of its trip fingers 6 into position to operate the brush controlling cams of the corresponding 55 sets of brushes on all of the switches so that whichever of the finder switches is caused to move up has that set of brushes tripped that corresponds with the particular magnet that is at the time energized. 60 When the finder switch that has been in use is returned to its normal position, any one of the associated controlling cams that has been tripped is engaged and rotated in a reverse direction to separate its switch 65 brushes again and thus render them inactive.

Each of the line finder and cord selector switches has associated with it a commutator 7 which comprises a number of stationary commutator segments and a set of movable wipers carried at the top of the switch shaft 70 1 and co-operating with the stationary segments. This commutator serves to make and break a number of controlling circuits in the various stages of the movement of the switch shaft. 75

The finder selector FS, shown in Fig. 5, is also of the power-driven type and substantially like the switch shown in the patent to McQuarrie, hereinbefore referred to, but since only a single set of brushes is required, the brush selecting or tripping mechanism is omitted. 80

For controlling the circuits of the system there are employed a number of sequence switches which are shown at different points 85 and are designated 100, 300 and 500 respectively. These sequence switches may be of the type disclosed in the patent to Reynolds and Baldwin, No. 1,127,808, issued February 9, 1915. Each consists of an electro-magnetically controlled motor or driving mechanism and a number of associated switch springs. The switch springs associated with the sequence switch 100 are designated 101 to 113 inclusive. Those associated with 90 the sequence switch 300 are designated 301 to 311 inclusive; and those associated with sequence switch 500 are designated 501 to 521 inclusive. To each of the contacts associated with the various sequence switch cams 100 are applied certain numerals. These numerals in the case of the springs 101, 301 and 501 indicate the only positions of the associated sequence switch in which these particular contacts are open; the numerals 105 applied to all of the other contacts of each sequence switch indicate the only position of the particular associated switch in which the associate contacts are closed.

In Fig. 5, two allotter switches FA and 110 SA are shown for determining the order of precedence of the selection of main line finder switches and the order of precedence of the operation of cord selector switches. These allotter switches are step-by-step 115 switches of the well-known type each being provided with a single brush or wiper and a single row of bank contacts. The wiper of each allotter is adapted to be moved over its row of contacts by a stepping magnet which 120 moves the wiper one step at each energization.

The identification of the lines with respect to the class of service each is entitled to, is effected by means of an interrupting 125 device. This interrupting device, as shown in Fig. 4, may consist of a number of separate commutator disks assembled on the same shaft in a definite relation to each other and constantly rotated by means of 130

suitable power mechanism. Brushes bear upon the commutator disks and serve to complete electrical connection between the disks and the external connections. Disks 5 415, 418 and 419 are constantly connected to battery through the disk 420. The disks 413 and 417 are connected to ground through the medium of disk 414. The disks 415, 418 and 419 have various and different combinations 10 of conducting and insulating segments, the arrangement being such that the circuit in which each of these commutator disks is included is made and broken in a way that is different from that in which each of the 15 other disks makes and breaks its circuit. Commutator disk 419 interrupts its circuit once per revolution, disk 418 interrupts its circuit twice and disk 415 interrupts its circuit three times.

20 The disks 413 and 417 serve to produce the pick-up impulses, which impulses co-operate with the identifying impulses produced by disks 415, 418 and 419 in a manner hereinafter explained to control the operation 25 of the identifying mechanism associated with each operator's position. In order to simplify the drawing, the conductors leading from the brushes which engage the commutator disks 413 and 417, to the registering relay mechanism in Fig. 6 have not been shown, but the ends of these conductors have been designated in both Figs. 4 and 6 by the letters *a* and *b*.

35 *Preliminary connection to operator's position.*

The manner in which the system is organized will best be presented in connection with a description of the mode of its operation. It will be assumed that the subscriber 40 at station A initiates a call. The removal of the telephone receiver from its switch-hook closes a circuit that includes both windings of the line relay 8, the resting contacts of relay 9, and both limbs of the line. The line relay 8 is energized, and in closing its contact establishes a starting circuit for the group of primary line finders which has access to the subgroup in which 45 the line A is located. This circuit may be traced from ground at the armature of line relay 8, through the front contact of the armature, through the starting relays 400 of all idle primary line finders of the group, and through the common pilot alarm relay 401 to grounded battery. All idle primary finders PLF of the group are thereby 50 started up to hunt for the terminals of the calling line.

60 The start relay 400 of the finder PLF energizes over this starting circuit and at its left-hand armature closes a circuit for the stepping magnet 402, extending from the grounded pole of the battery through the 65 winding and self-interrupting armature con-

tacts of the magnet 402, through the left-hand armature and front contact of start relay 400, through the back contact and outer right-hand armature of test relay 403, through the test wiper 404 and the bank contact upon which it is resting at the time the switch started, and assuming that the multiple terminals upon which the switch is standing are the terminals of another non-calling or busy line of the group, thence to 70 ground at the back contact and grounded armature of the line relay of such line. At its outer right-hand armature and front contact relay 400 closes a circuit for relay 405 which is energized. The stepping magnet 80 energizes, stepping the finder switch one step to position its wipers upon the next set of bank terminals and interrupts its own circuit. This operation of the stepping magnet continues until the test wiper 404 85 engages the test terminal of the calling line from which ground has been removed at the back contact and armature of the energized line relay 8. Assuming that the switch PLF is the first of the group to reach the terminals of the calling line, the test relay 403, which is connected in a branch of the circuit of the stepping magnet 402 extending to ground at the front contact and armature of slow relay 405, but which was shunted by 90 ground encountered at the test terminals of non-calling lines, now energizes. Although the test relay 403 is now energized in series with magnet 402, the magnet 402 does not 95 energize because of the resistance of relay 403.

100 Test relay 403 upon energizing opens at its outer right-hand armature and back contact, the circuit of the stepping magnet 402 and closes a circuit through this armature and its grounded front contact for placing a busy potential on the multiple test terminals appearing before the finder switches which have access to the calling line. At its inner right-hand armature and front contact, relay 403 closes a circuit from grounded battery through resistance 406, over the wiper 407 and bank terminal upon which it is resting and through the winding of the cut-off relay 9 of the calling line to 110 ground. The cut-off relay energizes over this circuit and at its armature contacts opens the circuit of the line relay 8 which thereupon deenergizes, restoring at its armature and back contact the non-calling or 115 busy ground potential to the test terminals of the primary line finders, and opens at its front contact the starting circuits for all 120 switches of the group. All started switches thereupon come to rest. The potential connected through the winding of the cut-off relay by the energization of relay 403, further serves to place a calling potential upon the test terminals of the calling line appearing at the banks of the line finders LF. 125 130

At its left-hand armatures and front contacts, relay 403 closes a circuit for the relay 408 which extends from grounded battery through the right-hand winding of relay 408, through the inner right-hand armature and back contact of relay 409, to the inner left-hand armature and front contact of relay 403, over the wiper 410 and bank terminal upon which it is resting, over the scribe's line loop, back through the upper bank terminal and wiper 411, through the outer left-hand armature and front contact of relay 403, through the outer right-hand armature and back contact of relay 409, and thence to ground through the left-hand winding of relay 408. Relay 408 upon energizing over this circuit opens at its armature and back contact the initial starting circuit through the relay 400 and closes therefor a holding circuit extending from grounded battery through the pilot alarm relay 401, through the winding of relay 400, and thence to ground through the armature and front contact of relay 408.

Relay 400 upon energizing also removed ground potential at its outer right-hand armature and back contact, from the test conductor leading into the terminal bank of the secondary line switches SLF having access thereto, and closes at its inner right-hand armature and front contact a starting circuit for the secondary switch SLF, which extends from grounded battery through the start relay 522, through the lower contact of sequence switch spring 502 (1 and 2), and thence to ground at the inner right-hand armature and front contact of relay 400. Relay 522 energizes over this circuit and at its lower-most armature and front contact closes a circuit for the stepping magnet 523 of the secondary line finder which extends from grounded battery through the winding and interrupter contacts of magnet 523, through the lower-most armature and front contact of relay 522, through the lower contact of sequence switch spring 503 (1 and 2), through the back contact and right-hand armature of test relay 524, through the lower contact of sequence switch spring 504 (1 and 2), over test wiper 525 and the test terminal upon which it is resting, and if the bank terminals upon which the wipers of the switch are then resting lead to a primary line finder which has not been moved into connection with the calling line, thence to ground at the back contact and right-hand armature of relay 400 of such primary finder switch. The stepping magnet 523 upon energizing over this circuit moves the wipers of the secondary line switch SLF one step to the next set of bank terminals and opens its own circuit at its interrupter contacts. The stepping magnet continues to move the switch wipers over the terminal bank until the test wiper 525 encounters the test terminal of the connection circuit leading to the primary switch taken for use, when no ground potential is found on the test terminal. At this moment test relay 524, which has up to this time been held shunted by the ground encountered at the test terminals of the bank, becomes energized over a circuit extending from battery through the winding and interrupter contacts of the stepping magnet 523, through the winding of the test relay 524, through the lower contacts of sequence switch spring 505 (1 and 2), and thence to ground at the lower intermediate armature and front contact of start relay 522. The resistance of test relay 524 is such that the stepping magnet 523 does not energize in series therewith.

Test relay 524 upon energizing places a busy ground potential on the test terminal of the set of bank terminals of switch SLF, upon which the wipers have come to rest over a circuit extending from ground at the lower contacts of sequence switch spring 506 (1 and 2), front contact and right-hand armature of relay 524, lower contact of sequence switch spring 504 (1 and 2), through wiper 525, and thence to the test terminal. At its left-hand armature and front contact, relay 524 closes a circuit to move the sequence switch 500 from position 1 to position 2, extending from grounded battery through the magnet winding of sequence switch 500, lower left-hand contact of sequence switch spring 507 (1), and thence to ground at the armature and front contact of relay 524. Under the control of its master contact 501, the sequence switch moves out of position 1 and is brought to rest in position 2.

In position 2 of the sequence switch a circuit is closed from ground at the upper right-hand contact of sequence switch spring 508 (2 to 12), to the test wiper 525 to place a busy potential on the test terminal of the bank upon which the wipers of the switch SLF are resting, which is maintained through the twelfth position of the sequence switch and replaces the busy potential placed thereon upon the energization of relay 524, and which potential is removed as soon as the sequence switch moves out of position 2. In the second position of the sequence switch a circuit is also closed which may be traced from grounded battery through the winding of relay 409, through a bank terminal of switch SLF and wiper 526 resting thereon, and thence to ground through the lower left-hand contact of sequence switch spring 508 (2 to 12). Relay 409 upon energizing opens the circuit of relay 408 at its right-hand armatures and back contacts, thereby causing the deenergization of relays 400 and 405, and establishes at its left-hand armature and front contact a new holding ground for test relay 403 of the primary line finder to replace

the holding circuit heretofore maintained through the armature and front contact of relay 405. This circuit may be traced from 5 grounded battery through the winding and interrupter contacts of stepping magnet 402, through the winding of test relay 403, through the front contact and left-hand armature of relay 409, through the wiper 526 of switch SLF, and thence to ground at the 10 lower left-hand contact of sequence switch spring 508. At the upper grounded contact 15 of sequence switch spring 502 a holding circuit is established for the start relay 522 which is maintained through position 9 of sequence switch 500.

Upon the initial energization of start relay 522, a circuit was also closed for the stepping magnet 527 of the operator's position 20 finder switch OPF, extending from grounded battery through the winding and interrupter contacts of stepping magnet 527, through the upper intermediate armature and front contact of start relay 522, through the back contact and inner armature 25 of test relay 528 through the lower right-hand contact of sequence switch spring 509 (1 to 16), through the test wiper 529 and test terminal of the set of bank terminals upon which the wipers of switch 30 OPF are standing, and if the operator's position to which the set of terminals leads is busy, to ground at the armature and front contact of relay 200 (see Fig. 2), or to ground at the left-hand armature 35 and front contact of relay 600 (see Fig. 6). The stepping magnet 527 energizes over this circuit and advances the wipers of the switch OPF one step to the next set of bank contacts and interrupts its own circuit. If 40 the next operator's position is busy, the switch advances another step and thus continues to advance step-by-step until an idle operator's position is encountered, when no ground potential will be found to exist on 45 the test terminal of the bank of the switch. Assuming that the operator's position, shown in Figs. 2 and 3, is the first idle position tested for by the switch OPF, the stepping magnet will remain deenergized 50 when the test wiper 529 encounters the test terminal assigned to such position. Test relay 528, which has been shunted during the advance of the switch wipers over the terminals of busy operators' positions by 55 the ground potential at the test terminals of the bank, now energizes over a circuit extending from grounded battery, through the winding and interrupter contacts of stepping magnet 527, through the winding 60 of test relay 528, and thence to ground through the front contact and upper armature of relay 522. Stepping magnet 527 does not energize, however, in this circuit owing to the high resistance of test relay 65 528. Relay 528 upon energizing opens at

its inner armature and back contact, the initial energizing circuit through the stepping magnet 527, at its inner armature and front contact extends a busy ground potential from the upper armature and front contact 70 of relay 522 to the test terminal of the set of bank terminals upon which the switch wipers have been brought to rest to prevent the seizure of the same operator's position by a second finder switch, and at its outer 75 armature and front contact closes a circuit for moving the sequence switch 500 out of position 2 and into position 3. This latter circuit may be traced from grounded battery through the magnet winding of sequence switch, and through the winding of left-hand contact of sequence switch spring 80 510 (position 2).

Warning tone to selected operator.

In position 3 of the sequence switch a circuit is closed for giving the operator at the position selected a warning tone, which circuit may be traced from the secondary of the warning tone transformer 530, through 90 the upper left-hand contact of sequence switch spring 511 (3 to 11), over the lower heavy talking conductor, through wiper 531, and the bank contact upon which it is resting, and thence to ground through the 95 upper right-hand winding of the operator's repeating coil 201. The tone current flowing in this circuit produces by induction a tone current through the operator's receiver 202. The operator upon hearing this tone is 100 warned of the fact that a call is about to be extended to one of the cord circuits of her position.

In position 3 a circuit is also established 105 for the relay 532 for a purpose to be described hereinafter, this circuit extending from grounded battery through the winding of relay 532, through a bank terminal and switch wiper 533 resting thereon, and thence to ground at the upper left-hand 110 contact of sequence switch spring 512 (3 and 4).

Selection of idle pair of line finder and cord selector switches.

A circuit is now closed for the relay 534 which initiates the hunting movement of the finder selector switch FS which may be traced from grounded battery through the right-hand winding of relay 534, through 120 the lower right-hand contact of sequence switch spring 513 (3 to 9), and thence to ground at the lower left-hand contact of sequence switch springs 513 (3). Relay 534 upon energizing closes a circuit for moving 125 the sequence switch 500 out of position 3 and into position 4, which circuit may be traced from grounded battery through the magnet winding of the sequence switch, through the lower right-hand contact of sequence switch 130

spring 514 (3), and thence to ground at the front contact and right-hand armature of relay 534. As soon as the sequence switch moves out of position 3, the initial energizing circuit of relay 534 is opened, but upon its energization relay 534 has closed a circuit through its left-hand winding from grounded battery through the resistance 535, through its left-hand winding, through its 5 left-hand armature and front contact, through the lower left-hand contact of sequence switch spring 515 (3 to 5), through the test brush 536 and the test terminal of the set of bank terminals upon which the finder 10 selector brushes normally rest, and assuming that the paired line finder and cord selector switches accessible through this set of bank terminals is busy at this time, to ground at the lower right-hand contact of 15 sequence switch spring 102 (2 to 18). Relay 534 at its right-hand armature and front contact also closed a circuit for the updrive magnet 537 of the switch FS which extends from grounded battery through the winding 20 of the updrive magnet 537, through the upper left-hand contact of sequence switch spring 514 (4), and thence to ground at the front contact and right-hand armature of relay 534. The updrive magnet upon energizing 25 presses a depending extension of the switch shaft 1 against the constantly rotating updrive roller 3, thereby causing the switch shaft and brush set 2 to be moved upwardly over its bank of contacts. When 30 the brushes of the switch engage a set of bank terminals corresponding to an idle pair of line finder and cord selector switches LF and CS, no ground potential is encountered by the brush 536 upon the test terminal of 35 such set of bank terminals, since the sequence switch 100 of the idle pair of line finder and cord selector switches is resting in position 1 and sequence switch spring 102 is opened at its lower right-hand contact, 40 and, therefore, the holding circuit through the left-hand winding of test relay 534 is no longer complete. The relay 534 is, however, maintained energized until the switch brushes are properly centered on the selected 45 set of bank terminals, by a circuit extending through the left-hand winding of relay 534, through the upper right-hand contact of sequence switch 515 (3 and 4), and thence to ground through the conducting portion 538 of the switch commutator 7, and shaft wiper 539. As soon as the switch brushes become 50 properly centered upon the bank contacts, the shaft wiper 539 engages an insulating portion of the commutator and the relay 534 deenergizes.

Certain of the cord selectors CS have access only to operator's cords of certain positions, while other cord selectors have access to cords of other positions. In order to prevent the seizure of a cord selector for use

which does not have access to cord circuits of the operator's position which has been selected by the finder switch OPF, the relay 532 is provided, which, as hereinbefore described, was energized in positions 3 and 4 70 of the sequence switch 500. This relay upon energization placed a ground potential upon the bank contact 540 of each set of bank terminals connected to cord selectors not having access to the cords of the operator's 75 position selected. Assuming that the finder selector switch FS had been moved to such a set of terminals leading to an idle cord selector, the selector FS would not have been arrested with its brushes thereon, as hereinbefore described, since the energization of relay 534 would still have been maintained over a circuit extending from grounded battery through the right-hand winding of relay 534, through the lower right-hand contact of sequence switch spring 513 (3 to 9), through the upper left-hand contact of sequence switch spring 513 (3 and 4), through brush 541, bank contact 540, and thence to ground through the front contact and armature of relay 532. The switch FS would, therefore, continue hunting until an idle cord finder was found which has access to the cords of the selected operator's position.

Reverting now to that point in the establishment of the connection when relay 534 deenergized, a circuit was closed at the right-hand armature and back contact of said relay, which extends through the lower contact of sequence switch spring 516 for moving 95 the sequence switch 500 out of position 4 and through the coöperation of the master contact 501 into position 8. At its left-hand armature and back contact, relay 534 also closes a circuit for extending a busy ground potential to the test terminal of the set of bank contacts upon which the brushes of switch FS are now resting, which extends from ground at the lower left-hand contact 100 of sequence switch spring 512 (4 and 5), 110 through the back contact and left-hand armature of relay 534, through the lower left-hand contact of sequence switch spring 515 (3 to 5), and thence through the test brush 536 to the test terminal of the bank. As soon 115 as the sequence switch 500 leaves position 5, this circuit is interrupted, but a new busy potential circuit is closed directly from the test brush 536, through the lower left-hand contact of sequence switch spring 509 (5 to 120 14), through the inner armature and front contact of relay 528 and thence to ground at the upper armature and front contact of relay 522.

When the sequence switch 500 reaches position 8, a circuit is closed from grounded battery through resistance 535, through the contact of sequence switch spring 517 (8 to 11), over wiper 542 of the switch SLF and the bank terminal upon which it is resting, 130

through the wiper 412 of the primary line finder PLF and the bank terminal upon which it is resting, to the multiple bank test terminals 114 of the calling line, therefore 5 by placing a selectable calling potential upon the test terminals of the calling line appearing before all of the line finders which have access thereto. A circuit is also closed for the group brush trip magnet 115 corresponding 10 to the group in which the calling line is located, which circuit extends from grounded battery through the magnet 115, through the bank contact 543 and wiper 544 resting thereon, and thence to ground at the lower 15 right-hand contact of sequence switch spring 508 (8 to 10).

In position 8 of sequence switch 500 a circuit is also closed for the start relay 116 (Fig. 1) which extends from grounded battery 20 through resistance 117, lower contact of sequence switch spring 104, through the winding of relay 116, through the lower contacts of sequence switch spring 105, over one limb of the talking circuit, shown in 25 heavy lines, through the brush 545 of the switch FS, through the upper contact of sequence switch spring 516 and through the back contact and right-hand armature of relay 534 to ground. Relay 116 upon energizing 30 causes the energization of sequence switch magnet 100 to drive the sequence switch out of position 1 and into position 2, this circuit extending from grounded battery through magnet winding of the sequence 35 switch, through the upper contact of sequence switch spring 106 to ground at the left-hand armature and front contact of relay 116. In positions 2 to 18, inclusive, the sequence switch 100 connects busy ground 40 potential from the lower right-hand contact of sequence switch spring 102 (2 to 18), to the test terminals individual to the paired line finder and cord selector switches multiplied into the banks of all finder selector 45 switches FS having access thereto, to prevent seizure of these paired switches by other finder selectors.

The circuits of the system are now in condition for the operation of the line finder 50 switch LF for hunting for the terminals of the calling line. This function is, however, dependent upon the condition of the finder allotter switch FA, which, at this time, determines the precedence of calls. If there is 55 no other calling subscriber of the same group entitled at this time to a connection, the sequence switches 500 associated with all other selector finders FS of the group will be either in positions 1 to 4 or 11 to 18, and consequently 60 upon the movement of sequence switch 500 associated with the circuits shown in Fig. 5, a circuit is established for the relay 524 which extends from grounded battery through the stepping magnet 523 and 65 its interrupter contacts, through the relay

524, through the lower contact of sequence switch spring 518 (8), through the upper contacts of sequence switch springs 518 (11 to 4) of other sequence switches 500, to ground through the bank contact and wiper 70 546 of allotter FA. Relay 524 thereupon energizes, but owing to its resistance stepping magnet 523 does not energize. Relay 524 upon energizing closes a circuit for causing the movement of sequence switch 500 75 from position 8 into position 9, this circuit extending from grounded battery through the winding of sequence switch magnet 500, through the lower left-hand contact of sequence switch spring 507 to ground at the 80 left-hand armature and front contact of relay 524. At its right-hand armature and front contact, relay 524 closes a locking circuit for itself which may be traced from grounded battery at the stepping magnet 85 523, through the winding of relay 524, through the upper contact of sequence switch spring 506 (8 to 16), through the right-hand armature and front contact of relay 524, through the upper right-hand 90 contact of sequence switch spring 504 (8 to 11), through the brush 547 of the switch FS and the bank contact upon which it is then resting, through the left-hand contacts of sequence switch spring 107 (2 to 4) and (2 95 and 3), through the conducting portion of segment 118 of the commutator 7 of the line finder LF (Fig. 1), and thence to ground through the shaft wiper 119. Upon leaving position 8 the initial energizing circuit 100 through relay 524 is broken at sequence switch spring 518.

In position 9 of the sequence switch a circuit is closed for relay 534 which may be traced from grounded battery through the right-hand winding of relay 534, and thence to ground at the lower contacts of sequence switch spring 513 (3 to 9) and (9). Relay 534 is energized in this circuit and at its right-hand armature and front contact 105 closes a circuit for driving the sequence switch 100 (Fig. 1) out of position 2 and into position 3. This circuit extends from grounded battery through the magnet winding of sequence switch 100, through the lower left-hand contact of sequence switch spring 103 (2), through the bank contact 548 and the brush 549 of switch FS resting thereon, through the upper right-hand contact of sequence switch spring 514 (8 to 11) 110 to ground at the right-hand armature and front contact of relay 534. A circuit is also closed at the right-hand armature of relay 534 for causing the energization of the sequence switch magnet of sequence switch 500, which thereupon is driven out of position 9 and into position 10. This circuit extends from grounded battery through the winding of the magnet of sequence switch 125 500, through the lower contact of sequence 130

- switch spring 514 (9) to ground at the right-hand armature and front contact of relay 534. Upon leaving position 9 the initial energizing circuit 534 is broken 5 at the lower contact of sequence switch spring 513, but the relay is maintained energized through positions 2 and 3 of sequence switch 100 over a circuit extending from grounded battery through resistance 535, through the left-hand winding of relay 534, through its left-hand armature and front contact, through the lower right-hand contact of sequence switch spring 515 (8 to 11), through the brush 550 10 of the selector finder FS and the bank terminal upon which it is resting, through the lower left-hand contact of sequence switch spring 108 (2 and 3), through the upper contacts of sequence switch spring 20 105 (2 and 3) to ground. The holding circuit of start relay 522 is broken as soon as sequence switch 500 leaves position 9 at the upper contact of sequence switch spring 502, and relay 522 thereupon 25 energizes.

Operation of main line finder.

- In position 3 of sequence switch 100 a circuit is established for the updrive magnet 30 of line finder LF. This circuit may be traced from grounded battery through the winding of the updrive magnet 120, through the lower contacts of sequence switch spring 109 (3) and (3 to 12), through the bank 35 contact 548 and brush 549 of finder selector switch FS, through the upper right-hand contact of sequence switch spring 514 (8 to 11), and to ground at the front contact and right-hand armature of relay 534. The up- 40 drive magnet 120 energizes, thereby forcing the depending extension of the shaft 1 of switch LF against the constantly rotating roller 3. The brush sets 2 of the switch are thereupon moved upwardly. Upon the 45 upward movement of the switch shaft the set of brushes having access to the group of lines in which the calling line is located is tripped by a trip finger 6 on the trip rod 5. The finger 6 having been rotated into position 50 by the energized trip magnet 115, all in the well-known manner. Continued movement of the switch shaft 1 traverses the tripped set of brushes over the bank of contacts to which they have access.
- As soon as shaft wiper 119 moves off of the conducting portion of segment 118 of the commutator 7, the holding circuit of relay 524 is broken and relay 524 becomes de-energized closing at its left-hand armature 55 and back contact a circuit through the lower right-hand contact of sequence switch spring 507 (10) for driving the sequence switch into position 11, and closes at its right-hand armature and back contact a holding circuit 60 through the right-hand winding of re- lay 534, which may be traced from grounded battery through the right-hand winding of relay 534, through the upper contact of sequence switch spring 503 (10 and 11), through the back contact and right-hand armature of relay 524, through the upper right-hand contact of sequence switch spring 504 (8 to 11), through brush 547 of switch FS, through the left-hand contacts of sequence switch spring 107 (2 to 4) and (2 and 3), to commutator segment 118 and ground at shaft wiper 119 during the engagement of the wiper 119 with the conducting portion of the commutator. 65
- Upon the engagement of the switch brushes with the multiple terminals of the calling line, a shunt circuit is closed around the left-hand holding winding of relay 534 which extends from one terminal of the winding through the contact of sequence switch 517 (8 to 11), through the wiper 542 of switch SLF, through the wiper 412 of switch PLF, through the test terminal 114 of the calling line, through the test brush 121 of the line finder LF, through the lower left-hand contact of sequence switch spring 108 (2 and 3), through the brush 550 of finder selector FS, through the lower right-hand contact of sequence switch spring 515 (8 to 11), and thence to the other terminal 70 of the winding of relay 534, through the left-hand armature and front contact thereof. The establishment of this shunt circuit about the winding of relay 534 causes the flow of current through the left-hand winding to cease, but relay 534 is still held energized over the circuit previously traced through its right-hand winding until the brushes of switch LF are properly centered on the terminals of the calling line, when shaft wiper 119 will no longer engage the conducting portion of the commutator segment 118, and the circuit through the right-hand winding of relay 534 will, therefore, 75 be opened. Relay 534 now deenergizes and at its right-hand armature and front contact opens the previously traced circuit of the updrive magnet 120. The switch shaft of finder LF thereupon comes to rest. 80
- When relay 534 deenergizes a circuit is closed for energizing the magnet of the sequence switch 100 which may be traced from grounded battery through the magnet winding of sequence switch 100, through the lower contacts of sequence switch spring 110 (3) and (3 to 12), through the brush 545 of finder selector FS, through the upper contact of sequence switch spring 516 (8 to 11), and thence to ground at the right-hand armature and back contact of relay 534. 85 Upon its energization the sequence switch 100 moves out of position 3 and comes to rest at position 4. In position 4 of sequence switch 100 a busy potential is placed upon the test contact 124 of the calling line for 90
- 120
- 125
- 130

holding the cut-off relay 9 energized, which circuit may be traced from grounded battery through resistance 125 over the upper contacts of sequence switch spring 111 and 5 through brush 126 of the line finder LF.

At the time the line finder LF was testing for the multiple contacts of the calling line, had there been another line in the same sub-group upon whose multiple test terminal 10 114 a calling potential existed, the line finder LF would not have been arrested with its brushes upon the terminals of such line as no shunt circuit would have been connected around the winding of relay 534 upon the 15 engagement of the test brush 121 of the line finder with the test terminal 114 of such line. Thus, the only finder switch that is enabled to connect with a particular calling line is the finder switch which has been 20 started through circuits established by the seizure of that calling line by a primary and secondary finder switch.

Sequence switch 500 upon leaving position 10 opens the circuit of the line finder 25 trip magnet 115 at the lower right-hand contact of sequence switch spring 508. With sequence switch 500 in position 11 a circuit is closed for advancing finder allotter switch FA one step, which circuit may be traced 30 from battery through the winding of stepping magnet 560 and thence to ground at the upper contacts of sequence switch spring 519. In position 11 a circuit is also closed for driving the sequence switch 500 out of 35 position 11 and into position 14. This circuit may be traced from grounded battery through the magnet winding of sequence switch 500 through the upper left-hand contact of sequence switch spring 507 (11), 40 through the left-hand armature and back contact of relay 534, through the lower right-hand contact of sequence switch spring 515 (8 to 11), through brush 550 and the bank contact upon which it is resting, 45 through the upper left-hand contact of sequence switch spring 108 (4 and 5), and thence to ground at the normal contact of 50 122 of the commutator 7 of cord selector CS and the grounded shaft wiper 123. The system now awaits the determination of precedence of seizure of cords in the selected operator's position as determined by the cord selector allotter SA (Fig. 5).

55 *Setting of class of service register.*

As soon as sequence switch 500 moves into position 12 with sequence switch 100 in position 4, a temporary talking circuit is established between the calling subscriber A 60 and the operator's head set 0 over a circuit which may be traced through the heavy line conductors from grounded battery through the lower right hand winding of the operator's repeating coil 201, through the winding 65 of relay 203, over the bank contact 551 and

wiper 552 of switch OPF, through the lower contacts of sequence switch spring 519 (12 to 16), through the brush 545 of switch FS and the bank contact upon which it is resting, through the lower right-hand and upper left-hand contacts of sequence switch spring 110, over the brush 128 of switch LF, through the line loop of subscriber's station A, through the brush 127, through the upper left-hand and lower right-hand contacts of sequence switch spring 109, through brush 549 of switch FS, through the lower contacts of sequence switch spring 511 (12 to 16), through the wiper 531 of switch OPF, and thence to ground through the upper right-hand winding of repeating coil 201. Relay 203 is energized over this circuit and closes a circuit for the slow acting relay 600 of the class of service register individual to the selected operator's position. This circuit may be traced from grounded battery through the winding of relay 600 to ground at the armature and front contact of relay 203. Relay 600 upon being energized closes a new locking circuit for relay 528 extending 70 from ground at its left-hand armature, through wiper 529 of switch OPF, through the lower right-hand contact of sequence switch spring 509 (1 to 16), through the armature and front contact of relay 528 and to grounded battery at the winding of stepping magnet 527, and establishes a circuit for relay 601 over the No. 1 pick-up conductor *a* to the commutator disk 413 of the class of service interrupter, shown in Fig. 4. This circuit may be traced from grounded battery through the winding of relay 601, through the right-hand armature and front contact of relay 600, over the conductor *a*, through 75 the brush in engagement with the disk 413, and to ground at commutator disk 414. As soon as the disk 413 has been rotated into the proper position by its constantly rotating driving shaft, this circuit is completed and relay 601 becomes energized. The transmission of the pick-up impulse over conductor *a* immediately precedes the rotation of disks 415, 418 and 419 into positions effective for the transmission of class of service impulses 80 and insures that no impulses will be effective until the disks are in a particular rotary position. A circuit is now closed for relay 602 extending from grounded battery through the winding of relay 602, through 85 the back contact and left-hand armature of relay 603, and thence to ground at the front contact and armature of relay 601. Relay 602 is energized and locks itself up over a circuit extending through its right-hand armature and front contact, through the winding of relay 603, and thence to ground at the left-hand armature and front contact of relay 600. Relay 603 is now energized and 90 at its left-hand armature and back contact 95

opens the initial energizing circuit of relay 602.

- Upon the energization of relay 602 a circuit is closed, over which class of service indicating impulses may be sent for setting up the class of service register at the operator's position. Assuming that the calling subscriber is located in a private branch exchange and is entitled only to limited service, two series of class of service impulses will be sent to the operator's register. The first series of impulses will be sent from the commutator disk 415 for setting up section C of the class of service register over a circuit extending from grounded battery at the class of service interrupter, Fig. 4, through commutator disk 415, through the lowermost terminal of the bank of switch PLF, through wiper 416 resting thereon, through the middle terminal of switch SLF and wiper 553 resting thereon, through the lower half-hand and upper right-hand contacts of sequence switch spring 520 (3 to 16), through wiper 554 of switch OPF and the bank terminal upon which it is standing, through the front contact and left-hand armature of relay 602, through the winding of relay 605, and thence to ground at the outer left-hand contact of relay 604. Relay 605 in response to the first impulse over this circuit closes a circuit for the relay 606 of section C of the register, which may be traced from grounded battery through the winding of relay 606, through the back contact and inner right-hand armature of relay 609, through the back contact and right-hand armature of relay 611, through the back contact and right-hand armature of relay 610, through the back contact and outer right-hand armature of relay 609, through the back contact and left-hand armature of relay 612, and thence to ground at the front contact and armature of relay 605. Relay 606 upon energizing closes a locking circuit for itself extending through its winding and its right-hand armature and front contact, through the winding of relay 609, through the back contact and left-hand armature of relay 610, and thence to ground at the front contact and armature of relay 600. Relay 609 is energized in this circuit and at its armatures and back contacts opens the initial energizing circuit of relay 606, and its outer armature and front contact prepares a circuit for the relay 607. Upon the next response of relay 605 to a second impulse from the class of service interrupter, the relay 607 is energized over a circuit extending from grounded battery through the winding of relay 607, through the outer right-hand armature and front contact of relay 609, and thence to ground at the armature and front contact of relay 605 over the circuit previously traced. Relay 607 closes a locking circuit for itself

extending through its winding and right-hand armature contacts, through the winding of relay 610, through the back contact and left-hand armature of relay 611, and thence to ground at the front contact and left-hand armature of relay 600. Relay 610 is now energized and at its left-hand armature and back contact opens the locking circuit of relay 606, which, together with relay 609, is deenergized. Relay 609 upon deenergizing opens the initial energizing circuit of relay 607, and at its right-hand armature and back contact prepares a circuit for the relay 608. In response to the third energization of relay 605, a circuit is closed for relay 608 extending from grounded battery through the winding of relay 608, through the right-hand armature and front contact of relay 610, through the back contact and outer right-hand armature of relay 609 to ground through the armature and front contact of relay 605 over the circuit previously traced. Relay 608 is energized over this circuit and locks up over a circuit extending through its right-hand armature and front contact, through the winding of relay 611, and thence to ground at the left-hand armature and front contact of relay 600. Upon energizing relay 611 at its left-hand armature and back contact opens the locking circuit through relays 610 and 607, which thereupon become deenergized. It is, therefore, apparent from the foregoing that only one pair of register relays, namely, the pair last energized will remain in an energized condition.

Following the class of service impulses of the first series which determine the line characteristics of the calling line, an impulse is transmitted over the No. 2 pick-up conductor b for causing the energization of relay 612. This impulse of current flows over a circuit extending from grounded battery through the normally closed right-hand armature contacts of relay 612, through the right-hand armature and front contact of relay 603, over the No. 2 pick-up conductor b, through the No. 2 pick-up commutator disk 417, and to ground at the disk 414. Relay 612 is energized and at its right-hand armature closes a locking circuit for itself and opens its initial energizing circuit, the locking circuit extending to ground at the left-hand armature and front contact of relay 600. At its inner left-hand armature and front contact, relay 612 closes a circuit for the class of service lamp relay 613, which may be traced from grounded battery through the winding of relay 613, through the front contact and left-hand armature of relay 608, and thence to ground at the inner left-hand armature and front contact of relay 612. Relay 613 upon energizing closes at its upper armature and front contact a circuit for the indicating lamp 313, which,

in the case assumed, indicates to the operator that the calling subscriber is located at a private branch exchange, and the relay at its other armature contacts prepares circuits 5 which will be hereinafter described.

Following the termination of the impulse over the No. 2 pick-up conductor, a second series of impulses is transmitted from the class of service interrupter for setting up the 10 relays of section D of the class of service register in substantially the same manner as hereinbefore set forth in connection with the setting of section C. Briefly, the impulses of the second series causes the energization 15 and deenergization of relay 605 since relay 602 is now energized, which retransmits the impulses from its grounded armature contact through the outer left-hand armature and front contact of relay 612 to relays 614, 20 615 and 616 in succession. Assuming that there are three impulses in the series for the purpose of indicating that the calling subscriber's line is provided with a coin box, relay 616 energizes upon the reception of the 25 last impulse of the series and locks up over a circuit extending from grounded battery through its winding and its right-hand armature and front contact, through the winding of relay 617, and thence to ground 30 at the front contact and left-hand armature of relay 600. Following the termination of the second series of impulses, relay 601 again energizes by an impulse over the No. 1 pick-up conductor and at its armature and front 35 contact closes a circuit for relay 604, which circuit may be traced from grounded battery through the winding of relay 604, through the normally closed right-hand armature contacts of relay 604, through the left-hand armature and front contact of relay 603, and thence to ground at the armature and front contact of relay 601. Relay 604 upon energizing opens its initial 40 energizing circuit at its right-hand contacts and closes thereat a locking circuit which extends to ground at the left-hand armature and front contact of relay 600, and at its outer left-hand armature and back contact opens the circuit through relay 605 to prevent 45 the further operation of relay 605 in response to further impulses from the class of service interrupter, at its outer left-hand armature and front contact prepares a circuit for subsequently driving sequence switch 50 300 at the operator's position out of position 3, and at its inner left-hand armature and front contact closes a circuit for the class of service lamp relay 618. The circuit for relay 618 may be traced from grounded battery 55 through the winding of the relay, through the left-hand armature and front contact of relay 616, and thence to ground at the inner left-hand armature and front contact of relay 604. Relay 618 upon energizing closes a circuit at its upper armature 60 and front contact for the class of service lamp 314, and at its other armature contacts prepares circuits which will be described hereinafter.

Selection of cord circuit at operator's position. 70

The operator has now been warned that a calling line is about to be connected to one of her cord circuits and through the class of service lamps is apprised of the nature of the calling line and the class of service to which such line is entitled. During the setting of the operator's service indicating register, sequence switch 500 has been moved 75 in the functioning of the allotter SA, or if upon reaching position 14 there was no other call entitled to precedence, such sequence switch has proceeded into position 15. Under the assumption that no other cord selector is entitled to precedence of connection with the selected operator's position, upon reaching position 14, a circuit is closed for relay 524 which may be traced from grounded battery through the winding of stepping 80 magnet 523, through the armature contacts of magnet 523, through the winding of relay 524, through the lower contact of sequence switch spring 521, through the upper contacts of sequence switch springs 521' 85 (6 to 11) of other sequence switches 500, to ground at the bank contact and wiper of the allotter SA. Relay 524 is energized and at its right-hand armature and front contact closes a locking circuit through its winding 90 extending from grounded battery through the winding of stepping magnet 523 through the winding of relay 524, through the upper contact of sequence switch spring 506 (8 to 95 16), through the front contact and right-hand armature of relay 524, through the upper left-hand contact of sequence switch spring 504 (14 to 15), through brush 550 of finder selector FS and the bank contact upon which it is resting, through the upper left-hand 100 contact of sequence switch spring 108 (4 and 5), and thence to ground at the normal segment 122 and shaft wiper 123 of the commutator 7 of switch CS. At its left-hand armature and front contact a circuit is closed 105 from ground through the lower left-hand contact of sequence switch spring 507 (14) for driving the sequence switch 500 out of position 14 and into position 15. In position 15 a circuit is closed from ground over the 110 upper contacts of sequence switch spring 505 (15) for the stepping magnet 557 of the allotter SA which moves its bush to the 115 next contact of its bank.

With sequence switch 500 in position 15 120 and sequence switch 100 in position 4, a circuit is now closed for the start relay 116 of the cord selector switch CS, which circuit may be traced from grounded battery 125 through resistance 117, through the lower 130

contact of sequence switch spring 104, through the winding of start relay 116, through the lower contacts of sequence switch spring 107 (4 and 5) and (2 to 4), 5 through the brush 547 of switch FS, through the upper left-hand contact of sequence switch spring 509 (15 and 16), through the lower right-hand contact of sequence switch spring 509 (1 to 16), through wiper 529 of 10 the switch OPF, and the bank terminal upon which it is standing, and thence to ground at the front contact and left-hand armature of relay 600. Relay 116 upon energizing closes a circuit from ground at its left-hand 15 armature and front contact, through the upper contact of sequence switch spring 106 (4) for driving the sequence switch 100 into position 5. In position 5 a circuit is closed for the updrive magnet 129 of the cord selector CS which extends from grounded battery through the winding of the magnet 129, through the lower contact of sequence switch spring 106 (5), and thence to ground at the left-hand armature and front contact 20 of relay 116. Upon the energization of the updrive magnet 116, the depending extension of the switch shaft 1 is pressed into contact with the constantly rotating roller 3, thereby causing an upward movement of 25 the switch shaft. The initial upward movement of the switch shaft carries the brush sets 2 of the switch past their respective tripping spindles 5, and since the tripping magnet 130 corresponding to the group of 30 cords at the selected operator's position is at this time energized over a circuit extending through the wiper 556 of the operator's position finder switch OPF to ground at the upper right-hand contact of sequence switch 35 spring 512 (14 and 15), the brush set 2 which has access to the cords of the selected position is tripped. Upon further upward movement of the switch shaft the tripped set of brushes is traversed over the terminals of its corresponding bank and, so long as the test brush 131 encounters a busy 40 ground potential upon the test terminals of the bank, the relay 116, whose initial energizing circuit was opened when sequence switch 100 left position 4, continues to remain energized over a locking circuit extending from grounded battery through resistance 117, through the lower contact of sequence switch spring 104 (1 to 5), through 45 the winding of relay 116, through the right-hand contacts of sequence switch spring 107, through the right-hand armature and front contact of relay 116, through the lower left-hand contact of sequence switch spring 112, 50 through the test brush 131. When the terminal of an idle cord is found, relay 116 is no longer held energized over the test brush 131 and becomes deenergized. It does not, however, release its armatures until after 55 the switch wipers have become centered on the bank terminals of the selected cord as its winding receives current over the circuit, above traced, through the lower left-hand contact of sequence switch spring 112, and from thence through the upper left-hand 70 contact of sequence switch spring 112 (4 and 5), through the segment 132 of the commutator 7 of the cord selector, and to ground through the shaft wiper 133. When the switch brushes are properly centered the 75 shaft wiper 133 is in engagement with an insulating portion of the segment 132 and the holding circuit of relay 116 is definitely broken.

Relay 116 upon deenergizing connects a 80 busy ground potential upon the test terminal of the selected cord circuit over a circuit extending from ground through the upper right-hand contact of sequence switch spring 113 (5 and 6), through the right-hand armature and back contact of relay 116, and thence through the lower left-hand contact of sequence switch spring 112 (4 to 6) to brush 131. At its left-hand armature and front contact relay 116 breaks the circuit 85 of the updrive magnet 129, and at its back contact closes a circuit extending through the lower right-hand contact of sequence switch spring 103 (5) for driving sequence switch 100 out of position 5 and under the 90 influence of its master contact 101 into position 12. In position 12 a talking circuit is closed from the calling subscriber's line, through the brushes of the line finder LF over the heavy conductors, through the upper contacts of sequence switch springs 109 and 110, through brushes of switch CS, and to the strands of the selected cord circuit. 95

When the switch CS moved from its normal position, the holding circuit of relay 105 524 was broken at the normal commutator segment 122 and relay 524 thereupon became deenergized closing at its left-hand armature and back contact a circuit through the lower right-hand contact of sequence switch 100 into position 16. In position 16 a circuit is closed for driving the sequence switch 100 out of position 12 and into position 14. 110 This circuit may be traced from grounded battery through the magnet winding of sequence switch 100, through the upper right-hand contact of sequence switch spring 108 (12), through the switch brush 550, and thence to ground through the upper right-hand and lower left-hand contacts of sequence switch spring 513 (16). Upon leaving position 12 sequence switch 100 opens a circuit which has held relay 203 at the operator's position energized, whereupon relay 203 deenergizes and opens the circuit of the slow-acting holding relay 600, which, after an interval, disconnects ground at its left-hand armature and back contact from the holding circuits of relays 602, 603, 604, 120 125 130

- 608, 611, 612, 616 and 617 of the selected class of service register which thereupon become deenergized. Relay 600 also opens the circuit extending through wiper 529 of switch OPF which has held the relay 528 energized. Relay 528 deenergizes closing at its outer right-hand armature and back contact a circuit for driving sequence switch 500 out of position 16 and into position 18.
- 10 This circuit may be traced from grounded battery through the magnet winding of sequence switch 500, through the right-hand contact of sequence switch spring 510 (3 to 16), and thence to ground at the
- 15 back contact and armature of relay 528. The deenergization of relays 608 and 616 causes the deenergization of the lamp relays 613 and 618. All the circuits of the class of service register are now restored to normal condition.

Reversion of primary and secondary line finders, finder selector and operator's position selector to common use.

- 20 When the sequence switch 500 left position 12, the circuit which maintained the primary finder switch PLF busy was opened at the contacts of sequence switch spring 508 (2 to 12). Relay 409 thereupon became deenergized opening the holding circuit of relay 403. All the circuits of the primary finder switch are now in normal condition. Busy ground potential is also removed from the test wiper 525, thereby rendering the
- 25 bank terminals leading to the primary finder switch selectable by other secondary finder switches. In position 18 of sequence switch 500 a circuit is closed for the downdrive magnet 558 of the finder selector switch FS, which extends from grounded battery through the winding of the downdrive magnet 558, and thence to ground through the upper left-hand and lower right-hand contacts of sequence switch spring 520 (18).
- 30 The magnet 558 upon energizing presses the depending extension of the switch shaft against the constantly rotating downdrive roller 4, thereby causing the restoration of the switch shaft and brushes to normal. When the shaft wiper 539 engages the normal segment 559 of the commutator 7, a circuit is closed for driving sequence switch 500 out of position 18 and into normal position.
- 35 This circuit may be traced from grounded battery through the magnet winding of sequence switch 500, through the upper right-hand contact of sequence switch spring 507, and thence to ground through the normal contact 559 and shaft wiper 539. All of the
- 40 circuits of the finder selector are now in normal condition.

Returning now to the point in the establishment of the connection when sequence switch 100 was driven out of position 5 and

into position 12, when sequence switch 100 reached position 6, a circuit was closed over the lower right-hand contact of sequence switch spring 112 for placing a busy potential at the multiple test contacts of the selected cord circuit, and a circuit for energizing the relay 315 of the selected cord circuit. This circuit may be traced from grounded battery through the winding of relay 315, through the lower contact of the sequence switch spring 302 (1), through normally closed contacts of the operator's charge key K, through brush 134 of switch CS, and thence to ground at the upper right-hand contact of sequence switch spring 102 (6 to 10). Relay 315 is energized over this circuit and locks up over a circuit extending through its winding and right-hand armature and front contact to ground at the upper contact of sequence switch spring 303 (1 to 4). At its left-hand armature and front contact, relay 315 closes a circuit extending through the upper right-hand contact of sequence switch spring 304 (1) for driving sequence switch 300 into position 2. In position 2 sequence switch 300 closes a circuit for the answering sleeve relay 204, which extends from grounded battery through the winding of relay 204, through the back contact and outer left-hand armature of calling sleeve relay 316, through the upper contact of sequence switch spring 302 (2 to 18), through the normally closed contacts of charging key K, and to ground at sequence switch spring 102 over the circuit previously traced.

Relay 204 is energized over this circuit and at its outer right-hand armature and front contact connects a ground potential to the multiple test terminals 135 of the selected cord circuit in the banks of all cord selectors having access to such cord circuit to prevent seizure of the cord circuit by another cord selector. At its left-hand armature and front contact, relay 204 closes a circuit for the supervisory lamp 205, extending from grounding battery through the lamp 205, through the left-hand armature and front contact of relay 204, and thence to ground at the armature and back contact of the answering supervisory relay 206. A circuit is also closed at this time, provided the operator is at her position, for the common listening relay 207, which extends from grounded battery through the relay 207, through the inner right-hand armature and front contact of relay 204, through sequence switch contact 305 (2), through the normally closed contacts of the listening-in keys K', individual to the several cords of the operator's position, through the winding of the common listening-out relay 200, and thence to ground at the key contacts 208 of the operator's head set. Relays 200 and 207 energize over this circuit, relay 200 connecting ground potential over its armature and front

contact to the bank terminals of operator's position selecting switches OPF, which have access to the selected operator's position to mark such position as busy and unselectable, 5 and relay 207 closing a locking circuit for itself which extends from grounded battery through its winding, through the inner right-hand armature and front contact of relay 204, through the inner right-hand armature 10 and front contact of relay 207, through the back contact and left-hand armature of the listening-out relay 209, through the contact of the listening-out key K', through the winding of relay 210, through the normally 15 closed contacts of the individual listening-in keys K', and through the winding of relay 200 to ground at key 208. Upon energizing relay 207 also closes a circuit for moving the sequence switch 300 out of position 20 2 and into position 3, which circuit may be traced from grounded battery through the magnet winding of sequence switch 300 through the lower left-hand contact of sequence switch spring 304, and thence to 25 ground at the intermediate right-hand armature and front contact of relay 207. Upon leaving position 2 the initial energizing circuit for listening relay 207 is broken at sequence switch contact 305. At its left-hand armature and front contact the relay 30 207 also closes a circuit extending from grounded battery through the winding of the listening relay 211 individual to the selected cord, through the left-hand armature 35 and front contact of relay 207, and thence to ground at the armature and front contact of the listening-out relay 210, causing the energization of the listening-in relay 211, which at its uppermost and intermediate 40 lower armatures and front contacts connects the operator's head set to the talking conductors leading back to the bank terminals of the cord selector CS, and thence to the subscriber's station over the circuit previously 45 traced, and at its innermost lower contact 220 closes a shunt around the contacts of relay 214 for preventing the calling subscriber from releasing the connection before the operator has extended the connection to 50 the desired line. This sequence of operations has taken place during the setting of the operator's class of service register. If the register is completely set at the time sequence switch 300 reaches position 3, the 55 sequence switch will be immediately driven out of position 3 and will come to rest at a position determined by the setting of the register. Otherwise sequence switch 300 waits in position 3 until the register is set. 60 The circuit for driving the sequence switch out of position 3 extends from grounded battery through the magnet winding of the sequence switch 300, through the lower right-hand contact of sequence switch spring 304 65 (3), and thence to ground at the outer left-

hand armature and front contact of relay 604. Should the register become completely set prior to the movement of sequence switch 300 into position 3, the register might become restored to normal through the de- 70 energization of relay 600, as hereinbefore described. To delay such restoration sufficiently the relay 600 is made slow to release in any well-known manner.

Under the assumption that the calling 75 subscriber's line is located in a private branch exchange and provided with a coin collecting device, relays 613 and 618 have been energized by the setting of the class of service register, and have through their armatures and front contacts established a circuit extending from ground at the armature immediately above the winding of relay 613, through the front contact in engagement therewith, through the armature immediately 80 above the winding of relay 618 and its front contact, through the upper right-hand contact of sequence switch spring 306 (4 to 12), and thence through the right-hand armature and front contact and winding of relay 315. 85 Relay 315 is thus maintained energized through positions 4 to 12, inclusive of sequence switch 300, and the sequence switch upon leaving position 3 is driven through position 12 and comes to rest in position 13. 90 As hereinbefore explained, sequence switch 300 is driven out of position 3 by a circuit extending through the lower right-hand contact of sequence switch spring 304, and if relay 315 is locked up when sequence switch 100 300 reaches position 5, it continues in rotation by reason of the driving circuit therefor, extending through the upper right-hand contact of sequence switch spring 304, and thence to ground at the left-hand armature 105 and front contact of relay 315. The sequence switch 300 has now positioned its springs 307 and 308 in a position for establishing circuits to the class of service lamps 313 and 314 at any time the operator desires to re-flash these lamps to determine the class of service to which the calling subscriber is entitled.

Extension of call by the operator.

Upon observing the lighting of the answering supervisory lamp 305, the operator picks up the calling plug P of the cord corresponding to the lighted lamp, and after testing the sleeve of the jack of the desired 110 line to ascertain if the line is busy or idle, proceeds to extend the connection to such desired line in accordance with instructions received over the circuit extending from her head set 0 to the line of the calling subscriber through the brushes of the cord CS and the line finder LF.

The insertion of the calling plug P in the jack of the line of the desired subscriber's station B causes the energization of the 130

sleeve supervisory relay 316 in series with the cut-off relay of the line. At its outer right-hand armature and front contact, relay 316 closes a circuit for the common listening-out relay 209, which may be traced from grounded battery through the winding of relay 209, through the right-hand armature and back contact of relay 317, and thence to ground at the outer right-hand armature and front contact of relay 316. Relay 209 upon becoming energized opens the locking circuit of relay 207, which in turn opens the circuit of the listening-in relay 211, and causes the deenergization of relay 200. The deenergization of relay 200 removes the busy potential from the bank contacts of switch OPF, thereby rendering the operator's position accessible for receiving further incoming calls. At its outer right-hand armature and back contact relay 207 makes effective a circuit for relay 317, which extends from grounded battery through the winding of relay 317, through its normally closed left-hand armature contacts, through the back contact and outer right-hand armature of relay 207, and to ground through the right-hand armature and front contact of relay 209. Relay 317 is thereupon energized and locks up over a circuit extending through its winding, through the make contact of its left-hand armature, and thence to ground at the inner left-hand armature and front contact of relay 316. At its right-hand armature and back contact, relay 317 breaks the circuit of the common listening-out relay 209, which thereupon deenergizes, and at its right-hand armature and front contact establishes a circuit for the calling supervisory lamp 212. This circuit may be traced from grounded battery through the lamp 212, through the armature and back contact of calling supervisory relay 213, through the right-hand armature and front contact of relay 317, and thence to ground at the outer right-hand armature and front contact of relay 316.

At its inner right-hand armature and front contact, relay 316 connects a new holding ground to the multiple test terminals of the selected cord circuit appearing in the banks of all cord selectors having access to the selected cord to prevent seizure of the busy cord by another cord selector. Relay 316 at its outer left-hand armature and back contact also opens the initial energizing circuit of relay 204, but relay 204 is still held energized over a circuit extending through the armature and front contact of relay 214, through the upper contact of sequence switch spring 302 (2 to 18), through switch wiper 134, through the upper contact of sequence switch spring 104 (11 to 14), through the winding of relay 116, through the right-hand contacts of sequence switch spring 111 (11 to 14) and (4 to 14), through the brush 126

of the line finder switch LF, and to ground 65 through the winding of the cut-off relay 9 of the calling subscriber's line, since upon the extension of the calling line to the cord circuit the supervisory relay 206 has been energized and has established a circuit for 70 relay 214. The subscriber's cut-off relay 9 and the relay 116 are held energized in this circuit throughout the duration of the connection.

Ringing out upon called line.

75

Upon the energization of sleeve relay 316 a circuit is closed at its front contact and intermediate left-hand armature for applying ringing current to the line of the desired subscriber. Ringing relay 318 is energized over a circuit extending from grounded battery through the winding of ringing relay 318, through the armature and back contact of relay 319, through the armature and back contact of ringing cut-off relay 320, and thence to ground at the intermediate left-hand armature and front contact of relay 316. Relay 318 is energized and at its armatures and back contacts breaks the connection 90 between the talking strands of the cord circuit and the tip and ring contacts of plug P, and at its front contacts closes a circuit for applying ringing current to the called line, which circuit may be traced from a source of 95 ringing current (not shown), through the winding of the ringing cut-off relay 320, through the lower armature and front contact of ringing relay 318, over the ring contacts of plug P and jack J, over the subscriber's line loop, and through the ringer 321 and condenser 322 at substation B, through the tip contacts of the jack and plug, through the upper armature and front contact of relay 318, and thence to ground. Relay 320 does not receive sufficient current over 100 this circuit to energize, but upon the response of the called subscriber the resistance of the circuit is reduced and relay 320 energizes, removing at its armature and back contact a 110 shunt which has existed around the winding of relay 319. Relay 319 now energizes in series with relay 318 and at its armature and front contact closes a shunt around the winding of ringing relay 318, which thereupon deenergizes to disconnect the ringing generator from the called line and to reestablish a connection between the plug terminals and the strands of the cord circuit. Supervisory relay 213 is now energized over the talking circuit 115 extending to the substation B of the called line, and at its armature contact opens the circuit of the supervisory lamp 212.

Supervision of the established connection.

125

The operator, noting that the calling subscriber has successfully obtained his connection, may now proceed to charge the call in

accordance with the indication which has been given her by the class of service indicating lamps. Should the operator wish to refresh her memory as to the class of service 5 to which the subscriber is entitled, she presses the listening-in key K' , individual to the cord circuit employed in the established connection. A circuit is thereupon closed for the relay 207 which extends from grounded 10 battery through the winding of relay 207, through the inner right-hand armature and front contact of relay 204, through the make contact of key K' , through the winding of relay 200, and thence to ground at key contact 15 208. Relay 207 locks up over a circuit extending through its inner right-hand armature and front contact, through the armature and back contact of relay 209, through the contacts of listening-out key K^2 , through 20 the winding of relay 210, through the break contacts of key K' upon the release of such key, and to ground through the winding of relay 200. Relay 200 is energized to place a holding ground upon the multiple bank contacts 25 appearing in the banks of all operator's position finding switches having access to the operator's position for preventing the selection of the operator's position while she is engaged in supervising the call, and relay 210 is energized to complete the circuit of the 30 listening-in relay 211, as hereinbefore described. Listening-in relay 211 connects the operator's head set 0 across the talking strands of the cord circuit, and at its lowermost armature and front contact closes a circuit 35 for lighting the class of service lamps, in the case assumed, lamps 313 and 314 which were previously selected upon the setting of the operator's class of service register. The 40 circuit for lamp 313 extends from grounded battery through the lamp, through the lower left-hand contact of sequence switch spring 307 (13), through the lower-most armature and front contact of listening-in relay 211, 45 and thence to ground at the left-hand armature and back contact of relay 315. The circuit for lamp 314 extends from grounded battery through the lamp, through the lower right-hand contact of sequence switch spring 50 308 (13), through the lower-most armature and front contact of relay 211, and thence to ground at the left-hand armature and back contact of relay 315.

Under the assumption that the calling line 55 is equipped with a coin box and is not entitled to the desired call without payment of a token, the operator, upon observing this fact from the lighted class of service lamps 313 and 314, presses the charge key K . The 60 charge key opens at its normally closed contacts the holding circuit which has been maintaining relays 9, 116 and 204 energized, but establishes a new holding circuit for the cut-off relay 9 and for relay 116 which ex-

tends through the upper make contacts of 65 key K , through the right-hand contact of sequence switch spring 309 (13), and thence through the winding of the operator's position register relay 215 to battery. Relay 204 is now maintained energized over a circuit 70 extending from ground through resistance 224, through make contacts of the key K , through sequence switch contact 302 (2 to 18), through armature 220 of relay 211 and its front contact, and thence through the 75 winding of relay 204. At its lower-most contact key K closes a circuit for energizing the call charging relay 216 and the ring back relay 217. The circuit of relay 216 extends from grounded battery through the winding 80 of relay 216, through the contact of sequence switch spring 310 (13), and thence to ground at key K , and the circuit of relay 217 extends from battery through the winding of relay 217, through the contact of sequence switch 85 spring 311 (13) to ground at the key K . The energization of relay 217 opens the talking strands of the cord circuit at its back contacts, and at its front contacts connects the party line ringing and charging keys 90 K^3 to the incoming end of the cord circuit. A circuit is now established from a source of 110 volt coin collecting current through the pilot relay 218, through the armature and front contact of relay 216, through the normally closed contacts of the party line ringing and charging keys K^3 , through the upper armature and front contact of relay 217, over the calling subscriber's line loop, and through the collecting magnet of his coin 100 box (not shown), and to ground thereat for causing the collection of the token, all in the usual manner. The energization of relay 215 closes a circuit for the operator's position register 219.

After completing the charging of the call, the operator restores the charge key K and listens out on the cord by pressing the common listening-out key K^2 , which opens the circuit through relays 200, 207 and 210, 110 thereby causing the deenergization of listening-in relay 211, whereupon the cord circuit is restored to such a condition that conversation may proceed between subscriber A and subscriber B.

Had the calling subscriber's line been 115 equipped with a message register instead of a coin box, then the class of service register would have been so set as to drive sequence switch 300 into position 12, in which position, 120 upon the operation of the charging key K , a circuit would have been established for operating a message register connected in parallel with the cut-off relay of the calling line, as is the usual practice. At the operator's 125 position this circuit extends from the grounded registering battery, through the operator's position register relay 221,

through the left-hand contact of sequence switch spring 309 (12), and thence through the upper make contacts of key K, and over the circuit hereinbefore traced, through relay 116, and thence in parallel through the subscriber's cut-off relay 9 and the message register to ground. The current flowing in this circuit is sufficient to operate the subscriber's register, and through this operation to cause the energization of the marginal relay 221 at the operator's position, which, at its armature and front contact, closes a circuit for the operator's position register 219.

Had the calling subscriber's station been a party line station and entitled to flat rate service, then the class of service register would have been so set as to drive the sequence switch 300 into position 8, in which position, upon operation of the key K, a circuit would have been closed for operating the position register 219 at sequence switch spring 309 (7 to 11). If the calling subscriber had desired a connection with a party line on his own line, the operator, instead of extending the connection to the multiple jack of the calling line through the plug P, would instruct the calling subscriber to hang up temporarily and would then call back on the calling line by depressing the proper party line ringing key of the key set K³. Assuming that the operator depresses key 222, a circuit is closed from ground at its upper make contacts through armature 223 of relay 211, and its front contact and through the winding of ring-back relay 217. Relay 217 energizes and its front contacts connects the incoming end of the cord strands to the make contacts of the depressed ringing key 222, and from thence through the selected ringing generator. Restoration of the depressed keys restores the circuits of the cord to their proper condition for talking.

Restoration of the connection.

Upon the termination of the conversation the restoration of the called subscriber's receiver to its switch hook causes the deenergization of the calling supervisory relay 213 and the lighting of lamp 212. The restoration of the calling subscriber's receiver to its switchhook causes the deenergization of relay 206, which in turn opens the circuit of relay 214, but as relay 214 is slow to deenergize, relay 204 is held energized temporarily through its contacts and the circuit of the supervisory lamp 205 is, therefore, established. The operator upon observing that both supervisory lamps are lighted proceeds to pull down the connection by removing plug P from jack J of the called line. Relays 316, 317 and 319 thereupon deenergize. After an interval, slow relay 214 deenergizes and opens the holding circuit through relays

204, 116 and the cut-off relay 9 of the calling line.

Relay 204 upon deenergizing closes at its right-hand armature and back contact a circuit for driving sequence switch 300 into normal position. This circuit extends from grounded battery through the magnet winding of sequence switch 300, through the upper left-hand contacts of sequence switch spring 304 (3 to 18), and thence to ground at the armature of relay 204. The circuits at the operators' position are now restored to normal condition and in readiness for receiving further calls.

Relay 116 upon deenergizing closes at its left-hand armature and back contact a circuit for driving the sequence switch 100 out of position 14 and into position 17. This circuit extends from grounded battery through the magnet winding of sequence switch 100, through the lower right-hand contact of sequence switch spring 103 to ground at the armature of relay 116. In position 17 of sequence switch 100 a circuit is closed for the downdrive magnet 136 of the line finder LF, which circuit extends from grounded battery through the winding of the downdrive magnet 136, and thence to ground through the lower left-hand contact of sequence switch spring 113. The energization of magnet 136 presses the depending extension of shaft 1 against the constantly rotating downdrive roller 4; thereby causing the switch shaft to be driven downwardly into normal position. When the shaft reaches its normal position a circuit is closed for driving sequence switch 100 into position 18, which may be traced through the winding of sequence switch magnet, through the upper left-hand contact of sequence switch spring 103, and thence to ground through the segment 137 of commutator 7 and shaft wiper 138. In position 18 a circuit is closed for the downdrive magnet 139 of the cord selector switch CS, which circuit may be traced from grounded battery through the winding of the downdrive magnet 139, and thence through the lower right-hand contact of sequence switch 113 to ground. Upon the cord selector switch CS reaching its normal position, a circuit is closed for driving the sequence switch 100 into normal position 1, which circuit may be traced through the winding of the sequence switch magnet, through the upper right-hand contact of sequence switch spring 103 (18), and to ground through the segment 140 of commutator 7 and shaft wiper 133, which rests thereupon in the normal position of the shaft of switch CS. The deenergization of the cut-off relay 9 restores the control of the line relay 8 to the calling subscriber and all apparatus used in the establishment of the connection is now in normal position.

What is claimed is:

1. In an automatic telephone exchange system, a group of subscribers' lines, a plurality of operators' positions, a plurality of cord circuits at each position, means for connecting a subscriber's line with an operator's position over a path comprising an operator selecting circuit terminating in means for selecting an idle operator's position, and selector switches for establishing a connection between a calling line and said operator selecting circuit, and switching means for subsequently connecting the terminals of said calling line with a cord circuit of said selected position independent of said path.
2. In an automatic telephone exchange system, a group of subscribers' lines, a plurality of operators' positions, a plurality of cord circuits at each position, means for connecting a subscriber's line with an operator's position over a path comprising an operator selecting circuit terminating in means for selecting an idle operator's position, and primary and secondary finder switches for establishing a connection between a calling line and said operator selecting circuit, and switching means acting subsequent to the selection of said idle operator's position for connecting the terminals of said calling line with a cord circuit of said selected position independent of said path.
3. In an automatic telephone exchange system, a group of subscribers' lines divided into a plurality of subgroups, a plurality of operator's positions, a plurality of cord circuits at each position, means for connecting a subscriber's line with an operator's position over a path comprising an operator selecting circuit terminating in means for selecting an idle operator's position, and a group of finder switches for establishing a connection between calling lines of said group and said operator selecting circuit, said switches having access respectively to said subgroups of lines, and switching means for subsequently connecting the terminals of a calling line with a cord circuit of said selected position independent of said path.
4. In an automatic telephone exchange system, a group of subscribers' lines divided into a plurality of minor and major subgroups, a plurality of operators' positions, a plurality of cord circuits at each position, an operator selecting circuit terminating in means for selecting an idle operator's position, a group of primary finder switches for establishing a connection between calling lines of said group and said operator selecting circuit, said switches having access respectively to said minor subgroups of lines, and finder switches having access to said major subgroups for subsequently connect-
- ing a calling line with a cord circuit of said position.
5. In an automatic telephone exchange system, a group of subscribers' lines divided into a plurality of minor and major subgroups, a plurality of operators' positions, a plurality of cord circuits at each position, an operator selecting circuit terminating in means for selecting an idle operator's position, a group of rotary finder switches for establishing a connection between calling lines of said group and said operator selecting circuit, said switches having access respectively to said minor subgroup of lines, and line finder switches for subsequently connecting a calling line with a cord circuit of said position, each of said line finders being provided with a plurality of brush sets having access respectively to said major subgroups of lines.
6. In an automatic telephone exchange system, a group of subscribers' lines divided into a plurality of minor and major subgroups, a plurality of operators' positions, a plurality of cord circuits at each position, an operator selecting circuit terminating in means for selecting an idle operator's position, a group of rotary finder switches for establishing a connection between calling lines of said group and said operator selecting circuit, said switches having access respectively to said minor subgroup of lines, and paired line finder and cord selector switches for subsequently connecting a calling line with a cord circuit of said position, each of said line finders being provided with a plurality of brush sets having access respectively to said major subgroup of lines.
7. In an automatic telephone exchange system, a group of subscribers' lines divided into a plurality of minor and major subgroups, a plurality of operators' positions, a plurality of cord circuits at each position, an operator selecting circuit terminating in means for selecting an idle operator's position, a group of primary switches for establishing a connection between calling lines of said group and said operator selecting circuit, said switches having access respectively to said minor subgroup of lines, paired line finder and cord selector switches for subsequently connecting a calling line with a cord circuit of said position, each of said line finders being provided with a plurality of brush sets having access respectively to said major subgroup of lines, and means individual to said operator selecting circuit for connecting said circuit with an idle pair of line finder and cord selector switches.
8. In an automatic telephone exchange system, a group of subscribers' lines, a plurality of operators' positions, a plurality of cord circuits at each position, an operator

selecting circuit terminating in means for selecting an idle operator's position, a primary finder switch for completing a connection between a calling line and said operator selecting circuit, paired line finder and cord selector switches for connecting said calling line with a cord circuit of said position, and means individual to said operator selecting circuit for connecting said circuit with an idle pair of line finder and cord selector switches, whereby upon seizure of said paired switches a temporary talking connection is established between a calling line and said operator's position through said line finder, connecting means and operator's position selecting means, and subsequently a direct connection is established between said line and a cord circuit of said position through said line finder and said cord selector switches.

9. In an automatic telephone exchange system, a group of subscribers' lines, a plurality of operator's positions, a plurality of cord circuits at each position, an operator selecting circuit terminating in means for selecting an idle operator's position, a primary finder switch for establishing a connection between a calling line and the said operator selecting circuit, paired line finder and cord selector switches for connecting said calling line with a cord circuit of said position, switching means individual to said operator selecting circuit for connecting said circuit with an idle pair of line finder and cord selector switches, whereby upon seizure of said paired switches a temporary talking connection is established between the calling line and said operator's position through said line finder, connecting means and operator's position selecting means, and subsequently a direct connection is established between said line and a cord circuit of said position through said line finder and cord selector switches, and means for restoring said primary finder switch, said operator's position selecting means and said switching means upon the establishment of said direct connection.

10. In an automatic telephone exchange system, a group of subscribers' lines, a plurality of operators' positions, a plurality of cord circuits at each position, an operator selecting circuit terminating in means for selecting an idle operator's position, selector switches for establishing a connection between a calling line and said operator selecting circuit, means independent of said selector switches for subsequently connecting said calling line with a cord circuit of said selected position, and means for producing a warning tone at said operator's position upon the selection of said position for appraising the operator of a call incoming over one of the cord circuits of the position.

11. In an automatic telephone exchange system, a group of subscribers' lines, identifying means for producing a characteristic electrical condition in said line, a plurality of operators' positions, a plurality of cord circuits at each position, a class of service indicating device at each position, an operator selecting circuit terminating in means for selecting an idle operator's position, selector switches for establishing a connection between a calling line and said operator selecting circuit, means effective upon the establishment of said connection for operating said device in accordance with the characteristics of said calling line, and means independent of said selector switches for subsequently connecting said calling line with a cord circuit of said selected position.

12. In an automatic telephone exchange system, a group of subscribers' lines, identifying means for producing a characteristic electrical condition in said lines, a plurality of operators' positions, a plurality of cord circuits at each position, a class of service register at each position, indicating means under control of said register, means for establishing a connection between a calling line and an idle one of said operator's positions, means effective upon the establishment of said connection for setting said register and for operating said indicating means, means independent of said connecting means for subsequently connecting said calling line with a cord circuit of said selected condition, and means at said operator's position for listening-in on said latter connection and for reoperating said indicating means.

13. In an automatic telephone exchange system, a group of subscribers' lines divided into a plurality of minor and major subgroups, a link circuit, a group of primary finder switches for establishing a connection between calling lines of said group and said link circuit, said switches having access respectively to said minor subgroups of lines, main finder switches each provided with a plurality of brush sets having access respectively to said major subgroups of lines for connecting a calling line with said link circuit and means rendered effective by the operation of one of said primary finder switches for selecting the particular brush set of said main finder switch having access to the major subgroup in which the calling line terminates.

14. In an automatic telephone exchange system, a group of subscribers' lines divided into a plurality of minor and major subgroups, a plurality of operators' positions, a plurality of cord circuits at each position, an operator's selecting circuit terminating in means for selecting an idle operator's position, a group of primary finder switches for establishing a connection be-

tween calling lines of said group and said operator's selecting circuit, said switches having access respectively to said minor subgroups of lines, finder switches each provided with a plurality of brush sets having access respectively to said major subgroups of lines and means rendered effective by the

operation of one of said primary finder switches for selecting one of said brush sets.

In witness whereof I hereunto subscribe 10 my name this 24th day of November, A. D. 1919.

SAMUEL B. WILLIAMS, JR.
